UNITED STATES PATENT OFFICE.

ARTHUR HARRIS, OF CHICAGO, ILL., ASSIGNOR TO J. McGREGOR ADAMS.

LOCOMOTIVE HEAD-LIGHT.

SPECIFICATION forming part of Letters Patent No. 272,245, dated February 13, 1883.

Application filed December 16, 1882. (No model.)

To all whom it may concern:

Be it known that I, ARTHUR HARRIS, a citizen of the United States of America, residing at Chicago, in the county of Cook and State 5 of Illinois, have invented certain new and useful Improvements in Locomotive Head-Lights, of which the following is a specification, reference being had therein to the accompanying drawings.

10 This invention relates to improvements in means for displaying signals on locomotive head-lights; and, briefly considered, it consists in casting light directly from the lamp and main reflector forward into reflecting-boxes 15 opening into the front of the case and rim, and thence transmitting the light by reflection back to the rear of the case outside the main reflector to reflecting-surfaces placed on angles, and thence through boxes projecting beyond 20 the sides of the outer case for the display of signals at the fronts and sides of said boxes. The signals are thus made visible from the front and sides of the train.

In the accompanying drawings, Figure 1 is 25 a sectional plan of my improved head-light on the line $x x$ of Fig. 2, Fig. 2 being a side elevation of the invention.

Similar letters of reference indicate similar parts in both views.

30 A is the outer case of the head-light or lantern, and a its rim. The lamp-burner is represented at b . At front upper portions of the outer case are placed boxes c , which open at c' into the front of the case, and also into the 35 rim. The front walls of the boxes c are at their inner sides provided with mirrors or reflecting-surfaces c'' , standing somewhat at an angle, as shown, to cast back in the desired directions the light received thereon from the 40 burner b . At the rear of the case A , at the upper and outer corners thereof, and in the plane of the front boxes, c , are placed boxes d , having curved rear walls, the inner sides of 45 which are furnished with mirrors or reflectors e . The reflectors e are multiplied and suitably arranged to effect a proper convergence or concentration of the rays as a focus, and to effectively throw the light through the side

and front glasses, $d' d''$, of the boxes d . The glasses $d' d''$ may be white or colored, and 50 used either to designate the number or character of the train, or as "caution" or "danger" signals. In either case the glasses are made removable, so as to permit the interchange of 55 numbers or colors.

This invention may be applied to head-lights now in ordinary use.

I disclaim the invention set forth in Patent No. 225,299, granted March 9, 1880, to Michael Nicholson; and also that described in Patent No. 209,405, granted October 29, 1878, to William Kelley, reissued February 18, 1879, under No. 8,591, which patents cover the cutting of the rim. I also disclaim the cutting of the front of the outer case, which is shown and 65 claimed in Patent No. 234,410, granted November 16, 1880, to said Kelley.

I claim as my invention—

1. In a locomotive head-light, the combination of boxes opening into the front of the 70 outer case and rim, and provided with interior reflecting-surfaces, and boxes opening into the rear wall of the outer case, having internal reflecting-surfaces and transparent glasses, through which glasses light is transmitted by 75 reflection for signaling purposes, substantially as set forth.

2. In a locomotive head-light, the combination of boxes opening into the front of the outer case and rim, and provided with interior 80 reflecting-surfaces, and boxes opening into the rear wall of the outer case, having outer transparent signal-plates, and a multiplication of internal reflecting-surfaces set on angles to effect the convergence or concentration of the 85 rays reflected back thereon, and to cast them through the transparent plates for signaling purposes, substantially as set forth.

In testimony whereof I affix my signature, in presence of two witnesses, this 5th day of December, 1882.

ARTHUR HARRIS.

Witnesses:

L. A. GRAY,
